UNITED STATES PATENT OFFICE.

CHARLES A. HUSSEY, OF NEW YORK, N. Y., ASSIGNOR TO THE HUSSEY ELECTRIC COMPANY, OF SAME PLACE.

ELECTRIC-ARC LAMP.

SPECIFICATION forming part of Letters Patent No. 269,939, dated January 2, 1883.

Application filed May 23, 1882. (No model.)

To all whom it may concern:

Be it known that I, CHARLES A. HUSSEY, of New York, in the county and State of New York, have invented a certain new and useful Improvement in Electric Lamps, of which the following is a specification.

My present improvement consists in the combination, with a rod supporting a carbon, of clamping-pieces, an electro-magnet or solenoid, an armature or core therefor, arms pivoted at one end directly to said armature or core, and pivoted at the other end to said clamping-pieces, and stops for limiting the upward movement of the clamping-pieces, so as to cause them to act upon said rod.

The improvement also consists in other features, hereinafter described and claimed.

In the accompanying drawings, Figure 1 is a sectional elevation of an electric lamp embodying the improvement. Fig. 2 is a vertical section of certain parts of the same, taken in a plane at right angles to Fig. 1; and Fig. 3 is a horizontal section of the same.

Similar letters of reference designate corresponding parts in all the figures.

A designates the upper carbon, and B designates the lower carbon. They are both detachably secured in metal holders, the lower of which has adjacent to it a globe-holder, C. The holder of the upper carbon is connected to a metal rod, D, which extends up through a metal case, E. The lamp is suspended by two metallic rods, F F', to which the line-wires are fastened. These rods are insulated from the case E by gaskets of hard rubber, a, and secured to metal plugs b, which extend up through the top of the case.

E' E² designate rods (shown as of tubular form) extending downwardly from the case E, and supporting the lower-carbon holder. These rods are insulated from the case E by gaskets e of hard rubber.

G designates a solenoid arranged within the case E. A wire, c, extends from the metal plug b of the rod F to one end of the wire of the solenoid G, and a wire, c', leads from the other end of the wire of said solenoid to the case E. From the case E the circuit extends to the rod D; thence to the upper carbon; thence to the lower carbon; thence to the rod E'; and thence along a wire, c², to the plug b of the rod

F'. This is the main circuit of the lamp. The core G' of the solenoid consists of an annular piece of metal, and fits within the solenoid.

H designates a solenoid whose coil of wire 55 is of higher resistance. It is arranged a little lower than the solenoid G, and receives the core G' outside it, the core G⁴ inside it, and a connecting-piece over its upper end. One end of its coil is connected by a wire, d, to the wire c, or the plug b of the rod F, and the other end thereof is connected by a wire, d', with the wire c², or the plug b of the rod F'. It will therefore be seen that the solenoid H is in a derived circuit. Springs G², acting on lugs extending from the core G', tend to force it upward. These springs may be compressed or relaxed by means of screws G³ to adjust the lamp for electric currents of different potentials.

I designate two clamping-plates, which are of the form of segments of a cylinder, and are adapted to grip the rod D. They are pivoted to arms J, which at the outer ends are pivoted to the cores G' G⁴ of the solenoids. The upward motion of these clamping-plates is limited by stops K, attached to the cores G' G⁴, and their downward motion is limited by a stop or stops, L.

When an electric current is supplied to the 80 lamp the solenoid G is energized and raises the cores G' G⁴. The arms J are thereby made to force the clamping-pieces on the rod D with a toggle-like action, thereby locking the said rod and the upper carbon in position, and a considerable upward-and-downward movement of the arms is required to produce a comparatively slight movement of the clamping-pieces toward and from the rod to hold or release the latter. When the resistance in the main circuit is increased by the consumption of the carbons to a material extent the solenoid G becomes weakened, and as a greater quantity of the electric current is then forced into the derived circuit the solenoid H becomes correspondingly stronger. The cores G' G⁴ are therefore caused to descend. When the cores thus move the arms J, the clamping-pieces I, and the rod D descend with them until the said arms come in contact with the stops L. When the cores G' G⁴ descend farther the inner ends of the arms and the clamping-pieces are caused to

move through arc-shaped paths, and to thereby release the rod D. The rod D and the upper carbon then descend until the resistance in the main circuit is reduced to the normal amount. 5 This causes the amount of the electric current passing through the solenoid G to be increased, and the amount of the electric current passing through the solenoid H to be decreased. Hence the cores G' G⁴ are then caused to move upward. The arms J are thereby caused to press the clamping-pieces against the rod D with a toggle-like action and cause them to grip the rod and retain it in position. This operation is repeated as the resistance of the main circuit is caused to vary by the consumption of the carbons and the feeding of the upper carbon. 15

Preferably I combine with the stops K springs K', which exert a constant tendency to depress the clamping-pieces. Screws fitted 20 to the stops may be used to act on the clamping-pieces, if desirable, in lieu of the springs.

It will be seen that by my improvement I produce a very simple and desirable clutch for controlling the feed of the upper carbon of an 25 electric lamp.

Where but one lamp is to be arranged in a circuit, I may use one solenoid only, arranged in the main circuit, to operate the clamping-pieces. The core would then descend by its 30 gravity.

It is not absolutely necessary that the arms J should be pivoted to the clamping-pieces. The arms and clamping-pieces may be rigidly connected, if desirable.

35 The core G' of the solenoid G is made of cylindric or tubular form, and the core G⁴ of the solenoid H is of similar form, but much smaller. The two cores are connected by a piece of magnetic or diamagnetic material.

What I claim as my invention, and desire to 40 secure by Letters Patent, is—

1. In an electric lamp, the combination, with 45 a rod supporting a carbon, of clamping-pieces, an electro-magnet or solenoid, an armature or core therefor, arms pivoted at one end directly to said armature or core, and pivoted at the other end to said clamping-pieces, and stops for limiting the upward movement of the clamping-pieces, so as to cause them to act upon said rod, substantially as specified. 50

2. In an electric lamp, the combination, with 55 the rod D, of the clamping-pieces I, the arms J, the solenoid G, the core G' therefor, and the stops K L, substantially as specified.

3. In an electric lamp, the combination, with 60 a rod for supporting a carbon, and a clutch or locking device for said rod, of two solenoids, arranged one within the other, and located, one in a main circuit and the other in a derived circuit, and cores for said solenoids, consisting of two cylindric or tubular pieces and a connecting-piece, substantially as specified.

4. In an electric lamp, the combination, with 65 a rod for supporting a carbon, and a clutch for engaging with said rod, of two solenoids, arranged one within the other, and located, one in a main circuit and the other in a derived circuit, and cores for said solenoids, consisting of two cylindric or tubular pieces and a connecting-piece of diamagnetic material, 70 substantially as specified.

C. A. HUSSEY.
